HANDLE-BAR STEM

Frank W. Schwinn, Chicago, Ill.

Application December 18, 1940, Serial No. 370,634

2 Claims. (Cl. 287—54)

The present invention relates to a handlebar stem for bicycles and is particularly concerned with the development of an improved handlebar stem and a simplified and improved method of making such stem.

In the manufacture of bicycles it has been customary to forge the blanks for the handlebar stems to a form approximating their final shape. This shape included a straight cylindrical lower portion, and an angularly disposed upper portion. This bar was subsequently formed, by suitable grinding, drilling and slotting operations, into a handlebar clamp.

The finished handlebar stems are highly polished and plated, and, in the prior construction of such stems, the machining, polishing and plating operations performed thereon, were necessarily numerous and difficult, and were not adapted to low price, large quantity production methods on standard types of machines.

The forging of the blanks approximately to the shape of the finished stem required a large number of forging operations with the result that the blanks were frequently pitted, so that it was necessary to form the blanks with a relatively large excess amount of material which subsequently was removed by machining.

It is difficult to discover hidden flaws and weaknesses in a forging thus formed, and since the breaking of a handlebar stem in use is apt to have serious consequences, increased assurance of freedom from such hidden imperfections is of extreme importance.

An object of the present invention is to simplify and improve the manufacture of bicycle handlebar stems.

Another object is to develop an improved handlebar stem from a simple blank with a minimum number of operations and maximum economy of materials.

Another object is to develop a handlebar stem from a blank of maximum simplicity which will be readily machinable so that the blank, after machining, can be developed into an improved bicycle handlebar stem.

Other objects and advantages of the invention will be apparent from the following description and the accompanying drawing in which similar characters of reference indicate similar parts throughout the several views.

Referring to the drawing, of which there is one sheet,

Figure 1 is a view in perspective of a forged blank for a handlebar stem made according to

the present invention, the flash from a forging operation having been removed therefrom;

Figure 2 is a view in side elevation of the blank shown in Figure 1, after machining, an end portion thereof being broken away to show a longitudinal sectional view through the center of a hole therein;

Figure 3 is a view in perspective of the machined blank illustrated in Figure 2 after forming to final shape;

Figure 4 is a plan view of the formed, machined blank shown in Figure 3 with a bolt hole drilled therethrough; and

Figure 5 is a vertical longitudinal sectional view through a completed stem having its associated parts assembled therewith.

In Figure 1 of the drawing, the numeral 11 indicates generally a forged blank made according to the invention after the trimming of the flash, not shown, which projects laterally from substantially the horizontal median plane of the blank upon completion of a forging operation in a manner well known to the art. The blank 11 is formed with a cylindrical portion 12, a tapered neck portion 13, and a flattened head portion 14. The head 14 is formed with a depression 15 in one side thereof to form a portion of reduced thickness, the depression extending across the full width of the head portion 14. The bottom of said depression is preferably forged flat and smooth, and the ends of said depression are filleted and of cylindrical section with a radius of curvature approximately equal to that of a handlebar 16, such as is shown in Figure 5. Each of the fillets which comprise the curved ends of the depression 15, has a circumferential length equal to approximately one-fourth of the circumference of the handlebar 16 with which the stem is to be used, while the length of the intermediate flat portion is equal in length to slightly less than one-half of the circumference of such handlebar when bent to finished form.

The plane of the bottom of the depression 15 is tangent to the curve of each of the ends of the depression so that when the head 14 of the stem is formed by bending to the shape illustrated in Figure 5, it will conform to the shape of the handlebar 16.

The head 14 has two holes 17 and 18 therein one in each of the thicker end portions of said head, said holes preferably being punched while the piece is hot as a part or continuation of the forging process. The hole 17 is formed with a pair of laterally extending kerf-like recesses 19, as shown in Figures 3 and 4, to receive locking

fins 20 on a bolt 21 used to clamp the handlebar 16 in the finished stem as shown in Figure 5.

It has been customary in the manufacture of handlebar stems, initially to forge an oversize blank substantially to form, and then to grind the piece to size. The ground blank was drilled and slotted to provide the handlebar clamp, and the piece was then polished in three successive polishing operations, each of which was performed with a finer grained polishing medium than the preceding one, so that each polishing operation removed the fine scratches left by the preceding operation.

In making a handlebar stem according to the present invention, it is preferred to perform the grinding operations and the first two of such polishing operations while the piece is straight, as shown in Figures 1 and 2. The cylindrical stem 12, and tapered neck portion 13, being of round section, are well adapted to rapid, inexpensive machine grinding and polishing on standard type machines. The head portion 15 also, being of open form and principally of straight contours, can be easily and quickly ground and polished on standard type machines. The final polishing operation, which is performed with an extremely fine grained polish, and which removes practically no metal, is preferably performed after the piece has been bent to shape and after final machining operations have been performed, as illustrated in Figure 5, but before the piece is plated.

After the straight piece shown in Figure 2 has been ground and subjected to the first two polishing operations, as above set forth, the reduced thickness, recessed portion 15 of the head 14 is bent beyond the elastic limits of the material thereof around a mandrel, not shown, of approximately the same diameter as the handlebar 16 to form a handlebar clamping eye. As a result, the fibers of the material in the reduced thickness portion 15 are so stretched and re-aligned in the outer peripheral part of the clamping eye and compressed in the inner peripheral part of the eye that it will not spring back to the straight form but permanently retains the curved eye shape. The portion of the head 14 having the recess 15 therein, is of a length so proportioned to the circumference of the handlebar 16 as to leave a space 22 separating the head portions having the holes 17 and 18 therein, as illustrated in Figures 3 and 5, thus permitting the head portions to be drawn together by the bolt 21 for tightening the clamp thoroughly to the embraced portion of the handlebar.

The tapered neck portion 13 is bent laterally toward the side of the blank having the recess 15 therein, the bend in the present illustrated construction being through an angle of approximately 90 degrees. Both of the above mentioned bending operations are preferably performed while the piece is cold. If the blank is free from defects or hidden weaknesses, such cold bending will not affect its strength, but if a serious defect or hidden weakness exists, the piece will fail or will tend to kink at the point of flaw and may be scrapped. The bending of the piece to shape thus acts to test the blank for flaws.

A hole 23 is drilled lengthwise through the cylindrical portion 12 of the bolt, being continued in a straight line upwardly and through a side of the neck portion 13 as shown in Figures 4 and 5. The lower portion 24 of the hole 23 is counterbored to permit a slight lateral movement of a stem bolt 25, and the upper end of the

hole 23 is also enlarged as at 26 and is machined to provide a flat face 27 as by means of an end mill, not shown.

The stem bolt 25 is provided with an enlarged 5 cylindrical head portion 28 adapted to rest on the face 27 and to extend upwardly beyond the counterbored portion 26. The upper portion of the head 28 of the bolt 25 is of hexagonal shape as at 29 to permit turning the bolt with a wrench. 10 The lower end of the stem 12 is cut off at an angle acute to its axis as at 30 to provide a cam face to cooperate with a similarly disposed cam face 31 on a conventional wedge member 32.

The wedge member 32, which is preferably an 15 aluminum die casting, is of cylindrical shape, of approximately the same diameter as the portion 12 of the stem, and is made with an internally threaded bore 33 to receive the bolt 25 in a conventional manner.

20 The present structure is cheaper and easier to manufacture than the conventional type of handlebar stem for a number of reasons, as well as being less apt to have hidden flaws or defects which might result in failure of the stem while in use.

25 A considerable saving in material is accomplished because of the practicability of forging closer to finished dimensions as above set forth, which in turn has the desirable result of requiring the removal of less material to attain the finished dimensions. The handlebar bolt holes may be punched instead of being drilled as in the prior construction, while the drilling of a hole and the milling of a slot for the handlebar 30 35 clamp are eliminated and replaced by a simple bending operation.

30 These advantages are of course in addition to the important advantages which include the simplification of the grinding and polishing operations 40 achieved by my invention, and the cold forming to shape which discloses any dangerous hidden flaws or weaknesses in the forging.

35 While the description of the illustrative embodiment of the invention has been based on the making of the blank by forging, it will be apparent to those versed in the art that the blank can be made by other methods, such as by the machining of a blank bar or billet of bendable metal such as steel, and cutting or forming 45 50 such piece of metal to the form of the finished blank, such as that illustrated in Figure 1, by means of suitable machining operations.

55 The forming of the machined or partly machined blank to shape by the bending of the upper portion of the stem to offset the clamp from its original position of alignment with the lower or main portion of the stem, produces a structural change in the metal of the stem itself which constitutes a slight stretching of the metal on the outer side of the bend, and a tendency toward the compression of the metal on the inside of the bend. The set-up of these stresses 60 65 causes a rupture or deformation of the blank at the areas of bend in case of a rejectionable flaw in the piece.

70 The grinding and preliminary polishing operations above referred to, which are performed upon the piece while in the original or straight form, are preferably performed while the piece is being rotated, and when so performed, the finish produced upon the blank is substantially uniform throughout the entire area of circular cross section. This characteristic produces a uniform polish on the entire area after the piece 75 is bent to final shape, as illustrated in Figure 4,

and greatly facilitates the final polishing operation prior to plating.

While I have illustrated a preferred embodiment of my invention, many modifications may be made without departing from the spirit of the invention, and I do not wish to be limited to the precise details of construction set forth, but desire to avail myself of all changes within the scope of the appended claims.

Having thus described my invention, what I claim as new and desire to secure by Letters Patent of the United States, is:

1. A handlebar stem comprising a body of originally straight bar stock, but in the finished form having a substantially gooseneck shape, including a straight cylindrical lower portion adapted to fit within the fork stem of a bicycle, a head return bent and internally dimensioned to embrace a handlebar, the end portions of the head being in opposed spaced relation, means for drawing the opposed portions of the head together to effect tight frictional engagement between the head and the handlebar, an integral intermediate portion extending as a continuation of the upper end of the lower portion and of one of the end portions of the head, angularly to the axis of said lower portion, and lat-

erally spacing the head therefrom, and means for securing the stem in the fork stem of the bicycle including a stem bolt extending axially through said lower portion and having its head accessible to a wrench at the upper end of said lower portion.

2. A handlebar of substantially gooseneck shape comprising a substantially straight lower portion adapted to fit within the fork stem of a bicycle, a head which is return bent and internally conformed and dimensioned to embrace a handlebar, aligned apertures in said superposed spaced ends of the head, a bolt occupying said apertures whereby said ends may be drawn together to effect tight frictional engagement between the head and a handlebar embraced thereby, a curved intermediate portion integral with the straight lower portion and one of the ends of the head and serving laterally to space the head from said straight lower portion, and means for securing the stem in the fork stem of a bicycle, said last-mentioned means including a stem bolt extending axially through said straight lower portion and having its head accessible to a wrench at the upper end of said lower portion.
